(57) **CLAIM**

The ornamental design for the electric connector, as shown and described.

DESCRIPTION

FIG. 1 is a perspective view of a first embodiment of the electric connector, as viewed from top, front and right side, showing our new design;

FIG. 2 is a top plan view thereof;

FIG. 3 is a front elevational view thereof;

FIG. 4 is a right side elevational view thereof, a left side view thereof being a mirror image;

FIG. 5 is a rear elevational view thereof;

FIG. 6 is a bottom plan view thereof;

FIG. 7 is a rear and upper left perspective view thereof. The broken lines showing the mating connector, lead wires and baseplate are included for the purpose of illustrating environmental structure only and form no part of the claimed design;

FIG. 8 is a perspective view of a second embodiment of the electric connector, as viewed from top, front and right side;

FIG. 9 is a bottom plan view of the embodiment of FIG. 8;

FIG. 10 is a top plan view of the embodiment of FIG. 8;

FIG. 11 is a front elevational view of the embodiment of FIG. 8;

FIG. 12 is a right side view of the embodiment of FIG. 8, a left side view thereof being a mirror image; and,

FIG. 13 is a rear elevational view of the embodiment of FIG. 8.
